WEFT-DETECTOR FOR LOOMS.

1,221,768.

Specification of Letters Patent.

Patented Apr. 3, 1917.

Application filed August 2, 1915. Serial No. 43,089.

To all whom it may concern:

Be it known that I, EPPA H. RYON, a citizen of the United States, residing at Waltham, in the county of Middlesex and State 5 of Massachusetts, have invented a new and useful Weft-Detector for Looms, of which the following is a specification.

This invention relates to a weft detector for looms and particularly to that type of 10 weft detector designed for determining the substantial exhaustion of weft upon the weft carrier or bobbin in the active shuttle of a so-called "feeler" loom.

This type of loom is used for weaving 15 fabrics of the better grades in which the occurrence of incomplete picks of weft or filling is objectionable. It has been heretofore proposed to prevent such defects by causing the weft carried in the active shuttle to be 20 replaced by a fresh carrier before the weft or filling is entirely exhausted therefrom, and to attain this result various forms of weft detecting devices or feelers have been devised.

25 Many of these devices are designed to insert a fresh weft carrier when the carrier in use is reduced to a predetermined minimum diameter. Another form of detector mechanism operates in conjunction with a slotted bobbin, the feeler passing through the slot in the bobbin after the slot is uncovered by the substantial exhaustion of the weft. This 30 form of feeler has been found more reliable than the form first described but requires a special bobbin, a special shuttle, and a special transfer mechanism as the bobbin is necessarily positioned and held in the shuttle with the slot always in horizontal position.

40 It is the general object of my invention to provide an improved form of weft detector or feeler which shall retain all of the advantages of the "slotted-bobbin" type, while at the same time attaining simplicity of construction and increased reliability in operation.

With this object in view one important 45 feature of my invention relates to the provision of a plurality of detecting members each independently movable and each adapted to enter some one of a series of spaced holes or openings formed in the cylindrical barrel portion of a weft carrier or bobbin.

The several weft detecting members are

55 maintained normally in a position to render an actuating device operative to cause the insertion of a fresh weft carrier. So long as the holes of the bobbin are covered by the weft or filling the detecting members will be moved forward as the bobbin approaches its 60 forward limit of travel and will thus be carried out of the path of the actuating device. When the device is used with large bobbins having thick walls, it may be unnecessary to cut the holes 16 entirely through 65 the wall of the barrel. Accordingly, the words "hole" and "opening" as herein used are intended to cover any hole, opening or recess in the wall of the bobbin of sufficient depth to serve the purposes hereinafter 70 described, whether or not the opening extends entirely through the wall of the bobbin.

When the holes are uncovered by substantial exhaustion of the weft, one or more of the detecting members will register with the 75 holes in the bobbin and will be left in outer or rear position where they are engaged by the actuating device and render it operative.

Further features of my invention relate to certain arrangements and combinations 80 of parts which will be hereinafter described and more particularly pointed out in the appended claims.

A preferred form of my invention is 85 shown in the drawings, in which—

Figure 1 is a side elevation of my improved weft detector;

Fig. 2 is a top plan view of the parts shown in Fig. 1;

Fig. 3 is a sectional view taken along the 90 line 3—3 in Fig. 2;

Fig. 4 is a front elevation partly in section, the section being taken along the line 4—4 in Fig. 2, and

Fig. 5 is a development of the cylindrical 95 barrel portion of the bobbin.

Referring to the drawings, I have indicated a shuttle 10 having a slot 11 formed in the front side thereof and having a bobbin 12 secured therein by the usual shuttle 100 spring 13. The bobbin 12 is provided with a butt 14 engaging the spring 13 and also with a hollow cylindrical barrel portion 15 adjacent said butt 14. A plurality of radial holes 16 are formed in the barrel portion 15, 105 extending through the cylindrical walls into the inner recess of the bobbin, and angularly spaced with relation to each other as shown

in Fig. 8, reference to which figure will show that the holes 16 are so disposed that one or more of them will intercept any axial line which can be drawn along the periphery of the barrel 15.

To coöperate with the holes 16 in the bobbin 12, I provide a plurality of detecting members 20, which are shown in Fig. 3 as having the form of U-shaped rods mounted to slide longitudinally in a detector slide 21. The rods 20 are of much smaller diameter than the holes 16 and are so positioned that any hole 16 located in the horizontal plane of the rods 20 will be engaged and entered by one of the rods 20. Each rod 20 is connected to a separate bar 22 mounted to slide in one of a series of grooves formed in an arched projection 23 extending upwardly from the slide 21. The rods 20 and the bars 22 are normally maintained in their extreme outer or right hand positions, as viewed in Fig. 3, by a swinging plate 24 pivoted at 25 to the slide 21 and forced against the bars 22 by a spring-pressed plunger 26.

The slide 21 is itself mounted for longitudinal movement in a stand 27 pivoted at 28 to a bracket 29 rigidly secured to the loom frame by suitable fastenings (not shown).

Vertical adjustment of the detecting members 20 with reference to the bobbin 12 is attained by means of an adjusting screw 30 threaded to the bracket 29 and engaging the under side of the stand 27. The stand 27 is maintained in close engagement with the screw 30 by means of a tension spring 31 connected at its upper end to the stand 27 and at its lower end to the bracket 29.

The slide 21 is normally forced to the right (Fig. 3) by a coil spring 32 encircling a rod 33 which is screw threaded into a portion 34 of the stand 27 and which is provided with a shoulder 35 which engages a lug 36 projecting downwardly from the slide 21. At its left hand end the rod 33 formed in the stand 27.

The spring 32 engages the lug 36 and normally forces the slide 21 to the right until the lug engages the shoulder 35 on the rod 33. The normal position of the slide 21 may obviously be varied by adjusting the threaded rod 33 within the portion 34 of the stand 27.

While a fresh bobbin is being inserted in the shuttle it is desirable that the detecting members should be moved forward, or to the left as shown in the drawings, until they are beyond the path of the entering bobbin.

To accomplish such movement I provide a slotted plate 40 mounted to slide upon the side of the stand 27 and having a notch 41 therein engaging a flange 42 projecting laterally from the slide 21. The plate 40 at its forward end is provided with an out-turned

portion 43 positioned for engagement by a roll 44 mounted upon some convenient portion of the transfer mechanism (not shown).

When the slide 21 and the detecting members 20 are in their normal or right hand position the locking bars 22 extend into the path of movement of a floating lever 45 which forms a part of the actuating mechanism which controls the insertion of a fresh weft carrier or bobbin within the active shuttle. The lever 45 is pivoted at 46 to a rod 47 which is vertically movable in a bearing 48 and which may be connected for reciprocation to any convenient portion of the loom driving mechanism. At its left hand end the lever 45 is connected by a rod 49 to the mechanism which controls the transfer devices. This mechanism forms no part of my present invention and for a complete description thereof reference is made to my prior Patent No. 1,005,321, issued October 10, 1911.

For the purposes of this application it is sufficient to state that the lever 45 swings freely about its connection to the lower end of the rod 49 so long as the free movement of the right hand end of the lever 45 is not intercepted. When such movement is intercepted, as by one of the locking bars 22, the lever 45 thereafter swings about its point of contact with the bar 22, thus moving the rod 49 to initiate the operation of the transfer mechanism.

In winding the bobbins for use in my improved feeler it is desirable to wind a small portion *a* of the weft or filling upon the lower end of the bobbin and closely adjacent to the butt 14 before the regular traverse motion of the spinning frame is started in operation.

In the operation of my improved feeler, so long as the holes 16 are covered by one or more layers of weft or filling the entire series of detecting members 20 will be forced inward or forward as the bobbin approaches its forward limit of travel, thus removing all of the locking bars 22 from the path of the lever 45. When the weft upon the bobbin becomes exhausted to such an extent as to uncover the holes 16, one or more of these holes will be found in alignment with one or more of the detecting members 20 and on the next forward movement of the bobbin the corresponding detecting members will pass freely through the holes 16, thus remaining in their outer positions with their locking bars 22 in the path of movement of the lever 45, which lever is thus rendered operative to control the transfer devices.

By the provision of a plurality of holes 16 spaced both longitudinally and angularly from each other and also by forming the holes 16 of greater diameter than the detecting members 20 it becomes impossible to so position a bobbin in the shuttle that one or

more of the holes 16 shall not align with certain of the detecting members.

By this construction therefore I avoid the necessity of placing the bobbin in the shuttle in any predetermined position. Furthermore, by the longitudinal spacing of the holes 16 and the longitudinal arrangement of the series of detecting members 20 a considerable variation in the position of the shuttle within the shuttle box may be permitted without impairing the accuracy in operation of the detecting mechanism.

Having thus described my invention it will be evident that changes and modifications can be made therein by those skilled in the art without departing from the spirit and scope thereof as set forth in the claims, and I do not wish to be otherwise limited to the details herein disclosed, but what I

claim is:—

1. A weft detector for looms having, in combination, an actuating device controlling a transfer mechanism, a plurality of individual detecting members each comprising a sliding rod having a portion positioned to engage the bobbin, and a second portion normally positioned to directly engage said actuating device and to independently render the device operative, said detecting members being separately slidable from normal position by engagement with an unexhausted weft supply on the active bobbin.

2. A weft detector for looms having, in combination, an actuating device controlling a transfer mechanism, a plurality of individual detecting members each independently operable to indicate substantial exhaustion of the weft supply in the active shuttle, means independent of said members for moving said actuator, and a support for said members which prevents movement of said members with said actuator when engaged thereby, said members having portions positioned normally in the path of said actuator and directly rendering said actuator effective when engaged thereby and said members being separately and independently removable from such position by engagement with an unexhausted weft supply in the active shuttle.

3. A weft detector for looms having, in combination, an actuating device controlling a transfer mechanism, and a plurality of individual detecting members each independently effective to render said actuating device operable to renew the weft supply in the active shuttle, said members having portions positioned normally in the path of said actuator and being separately and independently removable from operative position by engagement with an unexhausted weft supply on the active bobbin, and said bobbin having a plurality of spaced openings therein adapted to coöperate with said members after the removal of the weft

thereover and thereby permitting certain of said members to remain in normal position to render said actuating device operative.

4. A weft detector for looms, comprising a plurality of independently movable detecting members each adapted to indicate absence of weft on the active bobbin, a support for said members, means for yieldingly forcing all of said members outward toward the bobbin and an actuating device controlling a transfer mechanism, said actuating device being under the control of said detecting members and being rendered operative by any one of said detecting members which remains in its outward position during the extreme forward movement of the weft carrier independently of the position of the remaining detecting members and of their support.

5. A weft detecting device having, in combination, an actuating device, a plurality of individual detecting members, a locking bar rigidly connected to each member, and yielding means to normally position each of said bars in the path of said actuating device, said detecting members being in position for engagement by a bobbin in an active shuttle having a plurality of holes extending radially through its cylindrical wall, thereby permitting a detecting member entering one of said holes to remain in outer position with its locking bar extending into the path of said actuating device during the extreme forward movement of the bobbin.

6. A weft detector for looms having, in combination, a slide, means to withdraw said slide during the transfer of a fresh weft carrier, a plurality of detecting devices each independently movable in said slide and each adapted to enter one of a series of holes angularly and axially disposed in the cylindrical barrel portion of the weft carrier, and an actuating device movable to engage a weft detecting member remaining in its outer position during the extreme forward movement of the weft carrier and rendered operative by such engagement to cause the transfer of a fresh weft carrier.

7. A weft detector having, in combination, an actuating device, a detector slide, a plurality of detecting members each independently movable in said slide, a locking bar connected to each detecting member, and means to normally position said members and bars with a portion of each bar extending into the path of movement of said actuating device, said members and bars being movable to inoperative position by engagement with the bobbin in the active shuttle and said bobbin having a plurality of radial holes extending through the cylindrical barrel thereof so positioned that one or more of the detecting members will enter said holes after the weft has been removed from over said holes as the bobbin moves

to extreme forward position, such members and locking bars thereby remaining in outward position and rendering the actuating device operative.

5 8. A weft detector for looms comprising a normally inoperative actuator controlling a transfer mechanism, means to give said actuator regularly repeated operative movements, and means to render said actuator effective during any one of said movements to operate the transfer mechanism, said means comprising a plurality of independently movable weft detecting members each

adapted to indicate absence of weft on the active bobbin, each of said members when 15 in normal position being effective to render said actuator operative, and being movable from normal position by engagement with an unexhausted weft supply on the active bobbin, and a single yieldingly actuated 20 member engaging all of said detecting members and effective to return all displaced detecting members to normal position.

In testimony whereof I have hereunto set my hand.

EPPA H. RYON.
